UNITED STATES PATENT OFFICE.

JAMES E. HAUGHTON AND GEORGE BERRY, OF MANCHESTER, ENGLAND.

SHUTTLE FOR LOOMS FOR WEAVING.

1,426,188.

Specification of Letters Patent. Patented Aug. 15, 1922.

Application filed March 15, 1921. Serial No. 452,525.

To all whom it may concern:

Be it known that we, JAMES EDWARD HAUGHTON, a British subject, residing at Higher Crumpsall, Manchester, county of 5 Lancaster, England, and GEORGE BERRY, a British subject, residing at Chatham Hill, Manchester, county of Lancaster, England, have invented certain new and useful Improvements in Shuttles for Looms for 10 Weaving, of which the following is a specification.

This invention relates to improvements in shuttles for looms for weaving and more particularly to self threading devices, or 15 fittings for attachment to shuttles to enable them to be threaded by hand, in which a guide block is inserted in the shuttle head to direct or present the yarn or thread to the eye.

20 The invention consists in the particular construction of guide block hereinafter shown and described, characterized by three portions, all preferably formed integrally, viz: a horizontal or approximately horizontal portion, an inclined portion and a vertical apertured plate disposed in a vertical plane at right angles to the other two portions, and to the longitudinal axis of the shuttle, said apertured plate forming a tension and anti-balloonning plate in front of 25 the yarn passage.

The invention will be fully described with reference to the accompanying drawings.

Fig. 1. is a plan of shuttle head partly in 35 section with the guide block in position.

Fig. 2. is a side elevation of shuttle.

Fig. 3. is a section on line 3—3 Fig. 1.

Fig. 4. is a perspective view of the guide block and tension plate formed integrally.

40 Fig. 5. is a perspective view from the reverse side.

Fig. 6. is a perspective view of bottom member b with top member b' cut away.

Fig. 7. is a perspective view of modification of guide block B and tension plate C formed in separate pieces.

The shuttle head A is cut away at a to receive the guide block B and tension plate C. The two portions b , b' are joined together at 50 b^2 forming at their junction an acute angle, the upper portion b^1 being concave or curved and tapering towards its edges. The guide

block is set in the recess a in the shuttle head A with the lower portion b horizontal or approximately so and the upper portion b' inclined to the vertical. The junction of the two portions b , b' at b^2 forms a yarn passage b^3 which when in position opens into the eye a' of the shuttle. In front of the guide block B a member or plate C is fitted in a vertical plane at right angles to the longitudinal axis of the shuttle. The portion or plate C has a hole to receive the yarn or thread from the shuttle peg D and said portion or plate C is preferably formed 65 integral with the portions b and b' . This plate prevents the yarn or thread from ballooning out of place between the two portions b , b' when threaded and also assists in directing the yarn or thread between the two 70 portions during the operation of threading the shuttle. It may be formed in one piece with the guide block B as shown in Fig. 4, or separate therefrom as shown in Fig. 7.

The guide block B is disposed in the recess a of the shuttle A in such a position that the front of the yarn passage formed at the junction of the two portions b , b' is in line with the shuttle peg D and the back of the yarn passage b^3 formed between the 75 two portions extends or projects into the eye a' in the side of the shuttle.

A pin E of wood or other material is inserted through the side of the shuttle and a metal pin F is inserted across the shuttle 80 eye adjacent to the passage b^3 .

The shuttle is threaded by passing the yarn around and under the inclined portion b' and pulling it back parallel to the axis of the shuttle. This causes the yarn to pass 85 through the hole in the plate C and between the portions b , b' into the passage b^3 and be presented on the side of the shuttle at the aperture or eye and the end can be readily pulled through.

90 What we claim as our invention and desire to protect by Letters Patent is:—

In a shuttle formed with a recess in its head, a guide block arranged in said recess, comprising three portions, one approximately horizontal, the second inclined thereto, and having a depression at their junction through which the yarn passes and is presented to the eye, the third portion having 100

an aperture for the yarn and arranged in front of the other two portions in a vertical plane at right angles to the longitudinal axis of the shuttle to direct the yarn and prevent it ballooning out of position between the other two portions.

In testimony whereof we have hereunto

set our hands in presence of two subscribing witnesses.

JAMES E. HAUGHTON.
GEORGE BERRY.
